MACHINE FOR USE IN THE MANUFACTURE
OF SHOESRobert H. Lawson, Beverly, Mass., assignor to
United Shoe Machinery Corporation, Paterson,
N. J., a Corporation of New Jersey

Application December 8, 1931. Serial No. 579,668

11 Claims. (Cl. 12—17)

The present invention relates to shoe machines of the type in which a shoe supported upon a jack and the means for operating on the shoe are moved relatively to transfer the point of 5 operation along the bottom margin of the shoe and in which the relative positions of the shoe and the operating means are changed as the point of operation is transferred along the shoe to present the shoe properly to the operating 10 means.

The invention is intended primarily as an improvement in automatic shoe machines of the type disclosed in applicant's prior Patent No. 1,706,609 dated March 26, 1929 and in applicant's 15 pending application Serial No. 295,080 filed July 24, 1928 which patent and application disclose automatic side lasting machines constructed and arranged to operate simultaneously along the opposite sides of the bottom margin of the shoe. 20 Certain features of the invention, however, are well adapted for use in automatic shoe machines for performing other operations and in machines which are not automatic or only partially automatic in operation. Except as hereinafter defined in the claims, therefore, the several features 25 of the invention are not limited to use in any particular type of machine.

In the machines of applicant's prior patent and application, the jack is pivotally mounted 30 relatively remote from the point of operation on the shoe to swing in directions extending transversely and longitudinally of the shoe, the transverse movement permitting the shoe to be located in the proper position transversely with 35 relation to the upper tensioning and securing devices and the longitudinal movement permitting the shoe to be fed to transfer the point of operation along the shoe. In order to support the shoe and cause it to be presented properly 40 to the upper tensioning and securing devices, the jack is supported in these machines so that it can move towards and from the upper tensioning and securing devices in a direction substantially perpendicular to the shoe bottom and so 45 that it can be tipped about the point of operation as a center to maintain the bottom of the shoe in the proper plane longitudinally of the shoe. To permit these movements of the jack in the 50 machines of applicant's prior patent and pending application, the lower end of a comparatively long horizontal arm is pivotally mounted to swing in vertical planes upon a frame which, in turn, is pivotally mounted upon a swinging lever or frame to swing in horizontal planes. As a 55 result of this construction, some difficulty has

been experienced in controlling the movements of the shoe so as to bring the shoe into the proper position for the successive operation of the upper tensioning and securing devices and to hold the shoe securely in position particularly 60 during the action of said devices.

In machines of the type disclosed in applicant's prior patent and pending application, in which an operation is performed simultaneously along opposite margins of a shoe bottom, 65 it is desirable that the shoe be maintained in a constant angular position with relation to the line of feed as the shoe is moved to transfer the point of operation along the shoe. To secure this result in the machines of applicant's 70 patent and pending application, it is necessary to mount the jack in its supporting arm so as to be capable of rotation about a vertical axis and to control the angular position of the jack by means of a parallel motion link, thereby 75 adding somewhat to the weight and complication of the jack supporting structure.

An object of the present invention is to improve the jack supporting structure of machines of the type hereinbefore referred to with 80 a view to remedying the defects above noted and, with this object in view, a feature of the invention contemplates the provision of a jack support mounted to move in a direction substantially perpendicular to the bottom surface 85 of the shoe, and a carrier for the support mounted to move in a direction extending longitudinally of the shoe, one and preferably both of said members being mounted for sliding, as 90 distinguished from swinging movement. By the use of sliding members, a simplified construction is provided and the jack is supported rigidly and securely in position and can be manipulated without the production of any lost motion or looseness in the parts. By mounting the 95 carrier for the jack support to slide in a direction extending longitudinally of the shoe, the provision of a rotatable connection between the jack and its support and a parallel motion controlling link are rendered unnecessary and the jack can be pivotally mounted directly upon its support. Also, the provision of a jack support which is mounted to slide in a direction perpendicular to the bottom surface of the shoe permits the use of a simpler and more efficient arrangement of springs for yieldingly forcing the shoe towards the devices for operating on the shoe.

In the machines of applicant's prior patent and pending application, the upper tensioning 110

and securing devices act to perform a lasting operation successively and progressively along the shoe. A feature of the present invention particularly applicable to these machines, but 5 also applicable to other machines for performing an operation successively and progressively along the bottom margin of a shoe contemplates the provision of means for locking the support for the jack during each successive 10 operation of the operating means.

The shoe supporting jack of the machine disclosed in applicant's pending application above referred to is provided with shoe supporting means in the form of heel and toe rests pivotally mounted in the jack frame to permit a tipping movement of the shoe about an axis extending longitudinally of the shoe in substantially the plane of the sole whereby the sole of the shoe can be brought into the desired plane 20 transversely of the shoe by the upward pressure of the shoe against the abutments forming a part of the upper tensioning and securing devices. A feature of the present invention contemplates the provision in a jack of this general 25 character of means for permitting a lateral adjustment of the shoe supporting means with relation to the axis about which the shoe can tip, thereby equalizing the pressure of the shoe against the abutments and adapting a machine provided with a jack of this character for satisfactory operation upon both right and left shoes and upon shoes built upon lasts having an excessive swing. In a jack provided with heel and 30 toe rests, this feature of the invention contemplates laterally adjusting either and preferably both of the rests.

In addition to the features of the invention above referred to, the present invention also consists in devices, combinations and arrangements of parts hereinafter described and claimed, which together with the advantages to be obtained thereby, will be readily understood by one skilled in the art from the following description taken in connection with the accompanying drawings in which Fig. 1 is a front elevation of a side lasting and fastening machine embodying the invention, portions of the frame or base of the machine being broken away to more clearly display the actuating parts; Fig. 2 is a side elevation of the machine illustrated in Fig. 1, looking from the left hand side, the base being shown in cross section; Fig. 3 is a horizontal section taken just below the top portion of the base, parts having been broken away 55 and removed; Fig. 4 is a view in side elevation on an enlarged scale of the jack supporting parts; Fig. 5 is a view in horizontal section along the line 5-5 of the parts shown in Fig. 4; Fig. 6 is a detail view of the last pin and a portion of its supporting members; Fig. 7 is a similar view of the toe rest and a portion of the immediate supporting members; and Fig. 8 is a plan view of the parts shown in Fig. 7.

The invention is herein illustrated as embodied in an automatic side lasting machine which, except for the features embodying the present invention and except as hereinafter described, is the same in the construction, arrangement and mode of operation of its various parts 70 as the machine disclosed in applicant's pending application Serial No. 295,080 hereinbefore referred to. The illustrated machine is provided with a jack indicated at 2 constructed and arranged to receive a last upon which are assembled a shoe upper and an insole, and with a

pair of lasting units, indicated at 4 and 6, each of which is provided with a presser-foot or abutment 8 arranged to bear against the insole of a shoe on the jack, with grippers and wipers for tensioning the shoe upper and working it into 80 lasted relation to the last and insole, and with staple forming and driving devices for securing the upper in that relation. The lasting units are mounted in the machine to move towards and from each other and are so located that the presser-feet or abutments 8 bear upon the shoe upper near its margin at opposite sides of the longitudinal central line of the sole and substantially in line with each other transversely of the sole. The two lasting units operate simultaneously upon opposite sides of the shoe upper, and each lasting unit operates progressively and successively along the side of the shoe to perform a lasting operation from the heel breast line to the tip line of the shoe. The jack is pivotally mounted at its lower end so that its upper end can swing inwardly and outwardly to locate the shoe transversely in the proper position with relation to the lasting units, and is also pivotally mounted so that it 100 can swing in a direction extending longitudinally of the shoe to transfer the point of operation of the lasting units along the shoe. The jack is yieldingly pressed upwardly to hold the sole of the shoe in contact with the abutments 105 8 of the lasting units and, as the shoe is fed by the longitudinal swinging movement of the jack, the transverse position of the shoe is controlled by the engagement of the abutments with the insole rib.

The upper tensioning and securing devices of the lasting heads are actuated and controlled from a cam shaft 10 which is driven from a driving mechanism indicated at 12 and which makes one revolution for each cycle of operations of 115 the upper tensioning and securing devices. As the lasting operation progresses along a shoe, the bottom or sole surface of the shoe adjacent the point of operation is maintained both transversely and longitudinally of the shoe by tipping 120 the shoe about an axis extending longitudinally of the shoe in substantially the plane of the sole and about an axis extending transversely of the shoe at the point of operation. To enable the 125 shoe to be tipped about the axis extending longitudinally of the shoe, the heel and toe supports for the shoe are mounted in the jack frame so as to swing freely about this longitudinal axis and thus permit the shoe to be tipped 130 into the desired transverse plane by the pressure of the sole at opposite sides of the center line of the sole against the abutments 8 of the lasting units. To enable the shoe to be tipped about the transverse axis through the points of contact of the abutments 8, the jack is mounted at 135 its lower end upon a movable support so arranged that the movement of the support swings the entire jack about the line joining the abutments 8 as a center. The movements of this support are produced and controlled through connections actuated from a pattern cam shaft, indicated at 14. The movements of the jack to transfer the point of operation of the lasting units along the shoe are also produced through suitable connections from this cam shaft. The pattern cam shaft makes one revolution during the side lasting of a single shoe and is driven 145 from the driving mechanism 12. After the machine is started, the upper tensioning and securing devices continue in operation until the 150

side lasting of the upper has been completed. The upper tensioning and securing devices then cease to operate, but certain parts of the machine continue in operation and produce a downward

5 ward and outward movement of the jack and a return of the jack to the original position in which the shoe to be operated upon was placed on the jack. Also, during this return movement of the jack, the supports for the shoe are relatively actuated to unclamp the shoe to permit its ready removal from the jack.

10 Except for the constructions hereinafter specifically described as embodying the several features of the present invention, the various parts 15 of the machine so far referred to are the same in construction and arrangement as the corresponding parts of the machine of applicant's prior application and, although many of these parts are illustrated in the drawings, further 20 description is believed to be unnecessary.

As has been stated, a feature of the present invention relates to an improved and simplified structure for supporting the jack. In the illustrated embodiment of this feature, the lower 25 end of the jack spindle is pivotally mounted by means of a gimbal joint upon the upper end of a vertically movable slide indicated at 16. This slide is in the form of a comparatively long post 30 rectangular in cross section and mounted in its guideway so as to be incapable of any rotating movement about its axis. The guideway for the support is formed in a carrier 18 hereinafter described, and comprises two series of rolls 20 35 mounted in the carrier and arranged to bear against the four sides of the support, there being two series of these rolls with eight rolls in each series. The two series of rolls are separated so as to engage the support near its upper and lower ends and thus hold the support firmly 40 against displacement laterally in any direction, while permitting it to slide freely in a vertical direction. The rolls of each series are arranged to engage the support near its corners, at which points the support is provided with suitable wear 45 resisting strips 22. To force the jack support yieldingly upward so as to press the sole of a shoe on the jack against the abutments 8 of the lasting units, a comparatively long spring 24 is located within the support 16 which is made 50 hollow to receive it and is held between a seat at the upper end of the support and a disk 26 supported upon a screw 28 adjustably mounted in the carrier 18. To permit a comparatively 55 wide range in the up and down movement of the support 16 without materially affecting the force with which the shoe is pressed against the abutments of the lasting units, the spring 24 may consist of a number of nested spirals each 60 formed of comparatively light wire, but by their united action exerting the required upward force on the support.

A feature of the present invention is embodied 65 in means for locking the jack support against downward movement during each operation of the upper tensioning and stapling devices. As 70 illustrated, this locking means comprises a pinch dog or detent 30 fulcrumed on a bolt 32 extending through a portion of the carrier 18 parallel to one of the sides of the support 16. The detent 30 is provided with lugs to engage the guide strips 20 on one side of the support and, in order to receive the thrust exerted by the detent on the support, abutments 34 are 75 provided which are adjustably mounted in the

carrier 18 at the opposite side of the support from the detent. The detent is operated to lock and release the jack support in timed relation to the operation of the upper tensioning and securing devices by a cam 36 on the cam shaft 80 (see Fig. 2) through connections comprising a lever 38 pivoted on the machine frame and engaging at one end with a projecting arm 40 of the detent and a bell crank lever 42 having one arm in engagement with the cam 36 and the other arm connected by a link 44 to an arm of the lever 38. A spring 46 is stretched between one arm of the lever 38 and the frame of the machine and the arrangement of the cam 36 and connections to the detent 30 is such that the movement of the detent into locking position is produced by the action of the spring 46 while the movement of the detent in a direction to release the jack support is produced positively by the cam. The carrier 18 is mounted 85 to move on the machine frame in a direction extending longitudinally of the shoe, as will be hereinafter described and, to provide for this movement the arm of the lever 38 which engages the arm 40 of the detent is extended 90 in the direction of movement of the carrier, and is provided with a slot to receive the end of the arm 40.

The carrier 18 in which the jack support 16 is mounted for vertical sliding movement is 105 itself mounted for horizontal sliding movement on the frame of the machine. As illustrated, the carrier 18 is mounted to slide on a pair of rails 48 and 50 secured to the machine base one above the other and separated a sufficient distance to give firm support to the carrier. The rail 48 is provided with a V-shaped upper edge which is engaged by two widely separated grooved pulleys 52 on the carrier 18 and the rail 50 is provided with a V-shaped lower edge 110 which is engaged by two widely separated grooved pulleys 54 also mounted on the carrier. The carrier 18 is thus securely held against displacement but is permitted to slide freely and easily in a direction extending longitudinally of 115 the shoe on the jack.

In the illustrated machine, the sliding movements of the carrier 18 to tip the shoe about the point of operation so as to maintain the bottom of the shoe in the proper plane longitudinally of the shoe are produced through connections operated from the pattern cam shaft 14 comprising a chain 56 extending across the front of the machine (see Fig. 3) adjustably 120 attached to the carrier 18 by an eccentric bolt 58 mounted in a rearwardly extending arm of the carrier. The chain 56 is looped around a pulley 60 on the forward end of a lever 62, the rear end of which is engaged by a cam 125 on the pattern cam shaft 14. The chain 56 extends from the pulley 60 across the front of the machine and is secured to the left-hand side of the machine base. A movement of the pulley 60 to the right, as viewed in Fig. 3, exerts 130 a pull on the chain 56 and moves the carrier 18 a distance equal to twice the distance moved by the pulley. The carrier is moved in the opposite direction by connections comprising a chain 64 which extends from the arm of the carrier to which the chain 56 is secured, around a pulley 66 to one end of a long horizontal spring 68. The other end of the spring 68 is connected to one end of a chain 70 which passes 135 around a fixed pulley 72 and is connected at its 140 end to the carrier 18. The carrier is moved in the opposite direction by connections comprising a chain 74 which extends from the arm of the carrier to which the chain 64 is secured, around a pulley 76 to one end of a long horizontal spring 78. The other end of the spring 78 is connected to one end of a chain 80 which passes 145 around a fixed pulley 82 and is connected at its 150 end to the carrier 18.

other end to one end of a spring 74. The other end of this spring 74 is connected by a chain 76 to the base of the machine.

The jack of the illustrated machine is provided with heel and toe rests pivotally mounted so as to permit a tipping movement of the shoe about an axis extending longitudinally of the shoe in substantially the plane of the sole. Except for the construction which provides for a lateral adjustment of one or both of these rests, the jack is the same in the construction and arrangement of its parts as the jack of the machine disclosed in applicant's pending application. As illustrated, the jack comprises a U-shaped frame rigid with the upper end of the jack spindle, the lower end of which spindle is mounted by means of a gimbal joint on the upper end of the support 16. The toe rest for the shoe comprises a suitably shaped block 78 mounted upon a bracket 80 which is pivotally supported in one of the upwardly extending arms of the U-shaped frame. The pivotal axis of the bracket 80 is arranged so that it is in line substantially with the longitudinal central line of the bottom of the shoe supported on the jack. In order to permit a lateral adjustment of the toe rest so as to produce a corresponding lateral shift of the bottom of the shoe with relation to the pivotal axis about which the rest swings, the rest is mounted on a laterally extending guideway formed on the bracket 80 and is held in the desired lateral position on the guideway by means of a clamping screw 82 passing through a slot in the bracket into the rest. The heel rest comprises a last pin 84 which extends upwardly from a bracket pivotally supported, in line with the pivot of the bracket 80 of the toe rest, upon a longitudinally adjustable bar 86 mounted to slide in the other arm of the U-shaped frame. In order to permit a lateral adjustment of the last pin with a corresponding shift of the heel portion of the shoe with relation to the axis about which the heel and toe rests swing, the supporting bracket of the heel pin is made in two parts 88 and 90, the part 88 from which the heel pin projects being pivotally mounted at the lower end of the part 90 by means of a vertical pivot bolt 92, permitting the part 88 to be swung laterally with relation to the part 90. To hold the part 88 in any position to which it may be adjusted, a spring pressed locking pin 94 is mounted in the part 88 and arranged to engage any one of a series of holes formed in the lower end of the part 90. The lateral adjustment of the toe and heel rests permits the bottom of the shoe to be brought into a position in which the longitudinal central line of the sole corresponds substantially with the longitudinal axis about which the shoe is tipped by the pressure of the sole against the abutments of the lasting units. The shoe sole can thus be forced with equal pressure against the two abutments and the shoe can be securely held at both sides whether it is a right or a left shoe, or a shoe having an excessive swing. The lateral adjustment of the heel rest is of special value when shoes provided with narrow shanks are to be operated upon.

The jack of the illustrated machine is provided with shoe jacking and unjacking devices which are automatically actuated from a pulley 96 mounted in the jack support 16 through a gimbal joint and a shaft 98 extending from the gimbal joint upwardly through the jack spindle, the construction and operation being the same

as in the machine of applicant's prior application. On account of the manner in which the jack is supported, however, a slight change has been made in the arrangement of the guiding pulleys for the cable 98 which rotates the pulley 96. In the illustrated construction this cable leads from one side of the pulley directly to a guide roll 100 on the base of the machine and, from the other side of the pulley, leads to a guide roll 102 mounted upon the end of a freely swinging arm 104 pivoted on the machine base and thence to the drum which is actuated from the pattern cam shaft.

The nature and scope of the invention having been indicated, and a construction embodying the several features of the invention having been described, what is claimed is:

1. A machine for use in the manufacture of shoes having, in combination, a shoe supporting jack, devices for performing an operation progressively along the bottom margin of a shoe supported on the jack, a support on which the jack is pivotally mounted relatively remote from the point of operation to move in directions extending transversely and longitudinally of the shoe to locate the shoe transversely with relation to said devices and to transfer the point of operation along the shoe, and a carrier mounted to move during the operation on a shoe in a direction extending longitudinally of the shoe in which the jack support is mounted to slide in a direction substantially perpendicular to the bottom surface of the shoe to maintain said surface in the desired plane adjacent said devices.

2. A machine for use in the manufacture of shoes having, in combination, a shoe supporting jack, devices for performing an operation progressively along the bottom margin of a shoe supported on the jack, a support on which the jack is pivotally mounted relatively remote from the point of operation to move in directions extending transversely and longitudinally of the shoe to locate the shoe transversely with relation to said devices and to transfer the point of operation along the shoe, and a carrier mounted to slide during the operation on a shoe in a direction extending longitudinally of the shoe in which the support is mounted to move in a direction substantially perpendicular to the bottom surface of the shoe to maintain said surface in the desired plane adjacent said devices.

3. A machine for use in the manufacture of shoes having, in combination, a shoe supporting jack, devices for performing an operation progressively along the bottom margin of a shoe supported on the jack, a support on which the jack is pivotally mounted relatively remote from the point of operation to move in directions extending transversely and longitudinally of the shoe to locate the shoe transversely with relation to said devices and to transfer the point of operation along the shoe, a carrier mounted to move in a direction extending longitudinally of the shoe in which the jack support is mounted to slide in a direction substantially perpendicular to the bottom surface of the shoe to maintain said surface in the desired plane adjacent said devices, and means yieldingly forcing the support towards the point of operation.

4. A machine for use in the manufacture of shoes having, in combination, a shoe supporting jack, devices for performing an operation successively and progressively along the bottom margin of a shoe supported on the jack, a sup-

- port on which the jack is pivotally mounted relatively remote from the point of operation to move in directions extending transversely and longitudinally of the shoe to locate the shoe 5 transversely with relation to said devices and to transfer the point of operation along the shoe, a carrier mounted to move in a direction extending longitudinally of the shoe in which the jack support is mounted to slide in a direction 10 substantially perpendicular to the bottom surface of the shoe to maintain said surface in the desired plane adjacent said devices, and means for locking the support to the carrier against movement away from the point of operation during each successive operation of said devices. 15
5. A machine for use in the manufacture of shoes having, in combination, a shoe supporting jack, devices for performing an operation successively and progressively along the bottom margin of a shoe supported on the jack, a support 20 on which the jack is pivotally mounted relatively remote from the point of operation to move in directions extending transversely and longitudinally of the shoe to locate the shoe transversely with relation to said devices and to transfer the point of operation along the shoe, said support being movable in a direction substantially perpendicular to the bottom surface 25 of the shoe, means for yieldingly forcing the support towards the point of operation, and means for locking the support against movement away from the point of operation during each successive operation of said devices. 30
- 35 6. A machine for use in the manufacture of shoes having, in combination, a shoe supporting jack, devices for performing an operation progressively along the bottom margin of a shoe supported on the jack, a support comprising a hollow post on which the jack is pivotally mounted relatively remote from the point of operation to move in directions extending transversely and longitudinally of the shoe to locate the shoe transversely with relation to 40 said devices and to transfer the point of operation along the shoe, a carrier mounted to move in a direction extending longitudinally of the shoe provided with a guideway in which the hollow post is mounted to slide in a direction substantially perpendicular to the bottom surface of the shoe to maintain said surface in the desired plane adjacent said devices, and a spring located within the hollow post for yieldingly forcing the support towards the point of operation. 45
- 50 7. A machine for operating on shoes having, in combination, a shoe supporting jack, devices for performing an operation progressively along the bottom margin of a shoe supported on the jack, a support comprising a rectangular post on which the jack is pivotally mounted relatively 55
- remote from the point of operation to move in directions extending transversely and longitudinally of the shoe, and a carrier mounted to move in a direction extending longitudinally of the shoe provided with rolls arranged to form a guideway in which the jack support can slide in a direction substantially perpendicular to the bottom surface of the shoe. 60
8. A machine for operating on shoes having, in combination, a shoe supporting jack, devices for performing an operation progressively along the bottom margin of a shoe supported on the jack, a support on which the jack is pivotally mounted relatively remote from the point of operation to move in directions extending transversely and longitudinally of the shoe, a carrier in which the jack support is mounted to move in a direction substantially perpendicular to the bottom surface of the shoe, guiding rails for the carrier extending in straight lines longitudinally of the shoe, and rolls on the carrier engaging the rails. 65
9. A machine for use in the manufacture of shoes having, in combination, a jack comprising a frame and means for supporting a shoe in the frame while permitting the shoe to tip about an axis extending longitudinally of the shoe, abutments arranged to engage near its opposite marginal portions the sole of a shoe on the jack, means acting on the jack to force the shoe against said abutments and to tip the shoe about said axis, and means permitting an adjustment of the shoe supporting means laterally with relation to said axis. 70
10. A machine for use in the manufacture of shoes having, in combination, a shoe supporting jack having heel and toe supports, a frame on which the supports are pivotally mounted to permit a rocking movement of a shoe about an axis extending lengthwise of the shoe, abutments arranged to engage near its opposite marginal portions the sole of the shoe, means acting on the jack to force the shoe against said abutments, and adjustable connections between the toe supports and the jack frame to permit shifting the support laterally with relation to the axis of the rocking movement. 75
11. A machine for use in the manufacture of shoes having, in combination, a shoe supporting jack having heel and toe supports, a frame on which the supports are pivotally mounted to permit a rocking movement of the shoe about an axis extending lengthwise of the shoe, abutments arranged to engage near its opposite marginal portions the sole of the shoe, means acting on the jack to force the shoe against said abutments, and adjustable connections between the heel support and the jack frame to permit shifting the support laterally with relation to the axis of the rocking movement. 80

ROBERT H. LAWSON.
